UNITED STATES PATENT OFFICE.

VICTOR GRIFFITH, OF SAN FRANCISCO, CALIFORNIA.

COMBINATION LOCK AND EMERGENCY BRAKE FOR INTERNAL-COMBUSTION ENGINES.

Application filed April 10, 1923. Serial No. 631,243.

To all whom it may concern:

Be it known that I, VICTOR GRIFFITH, a citizen of the United States, and a resident of San Francisco, in the county of San Francisco and State of California, have invented certain new and useful Improvements in Combination Locks and Emergency Brakes for Internal-Combustion Engines, of which the following is a specification.

My invention relates to improvements in combination locks and emergency brakes for internal combustion engines, and it consists in the constructions, combinations and arrangements herein described and claimed.

An object of my invention is to provide a valvular means adjacent the gas-manifold whereby internal communication with the cylinders may be instantly and effectually cut off, thereby killing the engine temporarily and permitting the full energy of atmospheric pressure, through the open ends of the cylinders, to be expended upon the piston areas as a braking force.

Further objects and advantages will appear in the following specification, reference being had to the accompanying drawings, in which:—

Figure 1 is an elevation, showing my invention as installed between the flanges of a carburetor 5 and a gas-manifold 6, with its oblique stem extending within a dashboard.

Figure 2 is a longitudinal, partly sectioned, view, constructed in accordance with my invention, and illustrative of the position of the different parts during a cut off period.

Figure 3 is a vertical fragmentary detail, showing the piston, or plunger, the valvular opening therethrough and its obliquely and right faced extremities.

Figure 4 is a fragmentary plan, showing the manner of securing the foot portion of the device between the carburetor and gas-manifold flanges, and the jam-screws engaging the grooves of the screw-bolts and insuring against their removal.

Figure 5 is a detail, vertical and transverse, of a part of the foot portion of the device, showing the bore, the locked plug and the jam-screws.

Figure 6 is a detail, vertical section, showing the screw-plug in the stem portion of the device, positioned near its base and in

co-axial alignment with the bore of the foot portion of the device.

Referring more particularly to the drawings, A represents the housing, which is of approximate L-shape with 1 and 1', respectively, the foot and stem thereof. The foot and stem are bored longitudinally, the bores crossing at the juncture of the foot and stem, and have fitted therein plungers 2 and 2', the adjacent extremities of which 65 3 and 3' have obliquely fashioned surfaces adapted for slidable movement, the one over the other. The plunger 2 has near its farther extremity a transverse bore 4, registering, when in open or normal position, 70 with oppositely disposed openings 4' in the walls of the foot 1, which, in turn, are also in registration, respectively, with the openings through the flanges 5' and 6'. The plunger 2, in its cut off stroke, compresses a 75 spring 7, which operates upon release to return the plunger to normal position, or with its transverse bore 4 in registration with the openings transversely through the walls of foot 1 and also with those through 80 the flanges 5' and 6'. The foot 1 bears, exteriorly, surfaces fitted to receive flanges 5' and 6' and threaded openings into which are screwed threaded bolts 8, bearing annular grooves 8' for the engagement of the 85 points of jam-screws 9 entered from the seat of plug 10. The screw-plug 10 has a reduced in diameter portion 10' extending through the wall of the foot 1 and ending in a convex face, adapted, when the plug is 90 properly positioned, to conform to and form a section of the surface of the bore. The screw-plug 11 is of similar design to that of plug 10, and bears the same relation to plunger 2' as does plug 10 to plunger 2. 95 The plunger 2' carries on its lower extremity a seat 12 resting upon a spring 13, the purpose of which will be referred to later. The upper extremity of plunger 2' is of diminished diameter and is bored to receive 100 a lock-cylinder 15, carrying members 16, key-controlled and operating to lock plunger 2' in cut off position when these members are brought into engagement with the base of bushing 17. As here illustrated, the 105 communication between carburetor and engine is hermetically closed and locked.

When it is desired to return to normal, or position necessary to feed fuel to engine, the key 18 is operated to release members 110

from contact with base of bushing 17, upon which release the spring 13 restores plunger 2' to the dotted line position, releasing plunger 2 from pressure from this direction 5 and permitting spring 7 to restore this plunger to a position with its transverse bore in registration with all others between carburetor and gas-manifold.

Assuming the device dismantled and to be 10 assembled and installed, the foot 1 is placed between the flanges 5' and 6' with the stem 1' extending in the direction of and within the dash-board, as indicated in Figure 1, and the screw-bolts screwed into place. The jam- 15 screws 9 are then inserted obliquely from the seat of plug 10, through prepared openings, and set-up until heads are sunk and points are in engagement with the annular grooves 8'. The screw-plug 10 is next inserted and 20 screwed in until its convex face is in alignment with the surface of the bore and forming a section of it. The spring 7 is now inserted through the plug-opening 11 and forced to place and followed by the plunger 25 2. The plunger 2 after being forced to the extreme limit for non-registration of openings is there held awaiting further assembling, through the temporary insertion of a pin in a prepared-for-the-purpose opening 30 in wall and plunger, a plug being supplied for its closure after withdrawal of pin, as indicated at 19, Figure 3. The plug 11 follows and is screwed into position, in manner similar to that described for plug 10. The 35 plunger 2' is last assembled, bushing 17 excepted. After the insertion of the lock-cylinder 15 in the chamber prepared for it and the placing of a spring 13 at the bottom of bore in stem 1', the plunger 2' is inserted in 40 its bore with its obliquely-faced end down and paralleling the oblique face of plunger 2 and forced to and held in a position compressing spring 13 upon which its base 12 rests. The assemblage is completed by screwing 45 in the bushing 17, securing the lock-cylinder face to both lock-cylinder and plunger, withdrawing pin from 19 and closing opening with a screw-plug.

With communications between carburetor 50 and engine open, or normal, the plunger 2' occupies the dotted line position, with the key removed. For safety locking to prevent unauthorized use, a thrust of the hand sends plunger 2' down, forcing plunger 2 out, with 55 its transverse opening out of registration with other openings in fuel line to manifold, and creates an emergency air-pressure on piston area open to atmosphere.

While the construction and arrangement 60 of the device herein described and claimed is that of a generally preferred form, obviously modifications and changes may be made without departing from the spirit of the invention or the scope of the claims.

Having thus described my invention, I

claim, and desire to secure by Letters Patent:

1. The combination, in a device of the character described, with a carburetor and flange and a gas-manifold and flange, a member having a bore extending from one end to 70 within a short distance of the other end and surfaced sections adapted to receive flanges, threaded openings entering said sections with threaded bolts therefor having an annular groove near the ends thereof, jam-screws adapted to engage said annular 75 grooves, a plug-opening extending through the walls to the bore of said member and provided with a seat, a threaded plug for said opening having a seat and a diminished 80 and extended central portion ending in a concave face conforming to the surface of said bore of which it forms a section when properly positioned, a transverse bore extending through the walls of said member, 85 a plunger having a transverse bore there-through near one of its ends, the other of said ends being obliquely surfaced, means operating to thrust said plunger a predetermined distance in a certain direction, a compressible means borne in the closed end of 90 said bore operating to return said plunger to normal position upon the release from action of said operating means, and a means for automatically locking in position the said 95 plunger at the end of its stroke in either direction.

2. The combination, in a device of the character described, with a carburetor and flange and a gas-manifold and flange, a lockable valvular element comprising a sleeve having a transverse opening through the walls thereof and adapted to be secured between said flanges with the said transverse openings in registration with the openings 100 through said flanges, one end of said sleeve being closed by a wall-portion thereof and carrying a spring, the other end being threaded and fashioned with a seat and closed by a threaded plug having a diminished central 105 extension ending in a concave face, a plunger in said sleeve having an end obliquely fashioned and an end fashioned for abutment against said spring, a transverse bore 110 through said plunger near its spring abutment end, and means for the actuation of said plunger in manner to bring its transverse bore into or out of registration with the transverse openings in the walls of said sleeve.

3. In a device of the character described, a substantially L-shaped housing having legs axially at right angle and bores extending longitudinally therethrough and communicating at their juncture, plungers fitted, respectively, to said bores and having adjacent ends obliquely fashioned for slid able contact, a transverse bore through a leg of said housing and the plunger therein as normally positioned relative to each other, a 120

means, carried by the other of said legs, whereby the said plunger is forced into a position in which its transverse bore is out of registration with the transverse bore through 5 the said leg, and means for returning the said actuating means to the normal position.

4. In a device of the character described, a housing comprising a foot and a stem and having, respectively, longitudinal bores 10 therein with axes at right angles, threaded bolts bearing annular grooves for securing said foot in position, means, comprising a plug-closable opening and plug therefor and jam-screws, for locking said threaded bolts 15 against withdrawal, the said plug having a concave ending conforming to the surface of the bore, through which it is locked against removal when the plunger is occupying said bore, plungers fitted, respectively, to said bores, with adjacent ends obliquely 20 fashioned, the one plunger serving to actuate the other in one direction, means, comprising springs, for the movement of said plungers in the opposite direction, an opening in said stem in co-axial arrangement 25 with the bore of said foot, said opening serving for the introduction of the plunger belonging thereto, a plug for said opening's closure, and means for securing the plunger in said stem against recoil, when once forced 30 to the limit of its operating stroke, comprising a key-controlled element.

VICTOR GRIFFITH.
